JUVENILE TOILET SEAT

James S. Cothran, Charlotte, N. C.

Application March 26, 1935, Serial No. 13,082

2 Claims. (Cl. 4—239)

This invention relates to an auxiliary toilet seat for children and more especially to a seat which can be mounted as a permanent fixture in the ordinary bath room and used with a conventional toilet, and which can be folded against the wall when not in use.

It is, therefore, an object of this invention to provide a toilet seat of smaller dimensions than the conventional seat which may be used for children, said toilet seat being hingedly supported to the wall in the bath room in a manner so that it may be lowered to a position where it will be disposed above a conventional toilet stool.

It is a further object of this invention to provide an auxiliary toilet seat for children which is hingedly supported near the wall and adjustably secured to the wall so its position may be adjusted to conform to the distance of the toilet stool from the wall so that when it is raised to a position where the conventional or adult toilet seat might be used, the auxiliary seat will automatically fold. Means are also provided for holding the auxiliary toilet seat in raised position. When the seat is in this position, it will occupy less space and furnish no obstruction to the user of the conventional toilet.

Some of the objects of the invention having been stated, other objects will appear as the description proceeds, when taken in connection with the accompanying drawings, in which:—

Figure 1 is a plan view of my invention secured to the wall of a bath room;

Figure 2 is a front elevation of Figure 1;

Figure 3 is a vertical sectional view taken along line 3—3 in Figure 1;

Figure 4 is an elevation looking at the right-hand side of Figure 2;

Figure 5 is a sectional view similar to Figure 3 but showing the auxiliary toilet seat in folded or inoperative position;

Figure 6 is a plan view showing a modified form of mounting my invention;

Figure 7 is an isometric view of the bracket used for mounting the toilet seat in Figure 6.

Referring more specifically to the drawings, the numeral 10 denotes a side wall of a bath room to which is secured a strip 11 by any suitable means such as screws 12. Brackets 13 and 14 are secured to strip 11 by any suitable means such as nails or screws 15 and 16, and these brackets have grooves 17 and 18 respectively, in the outstanding leg thereof in which are mounted plates 19 and 20. Plates 19 and 20 have longitudinal slots 19a and 20a therein which are penetrated by bolts 21 and 22 respectively.

Since these bolts also penetrate the brackets 13 and 14, it is evident that the slots 19a and 20a furnish means for adjustment of the plates 19 and 20. Mounted in plates 19 and 20 is a rod 25 which acts as a pivot support for members 26 and 27. The other end of members 26 and 27 are adapted to support a toilet seat 28 having an opening 28a therein which rests above toilet fixture 29 which is shown in dotted lines in Figures 2 and 3.

By referring to Figures 1 and 2, it will be seen that the member 26 does not extend entirely across the toilet seat 28 but an additional block 26a is provided in order to provide sufficient bearing between the toilet seat 28 and the toilet fixture 29. An additional strut 30 is also disposed between the left-hand ends of members 26 and 27 for holding these members in spaced relation at this point.

Pivotedly mounted to the upper side of toilet seat 28 as at 32, is an upright member 33, and also pivotedly mounted on member 28, as at 34, is a similar upright member 35. A suitable strut or supporting member 36 is disposed between the lower ends of members 33 and 35 and mounted on top of these members is an arm rest 37. In a like manner supports 38 and 39 are pivotedly mounted on the upper side of member 28 as at 40 and 41, and these members have a strut 42 securing their lower ends together and also an arm rest 43 mounted on the top thereof. In order to provide a stop for members 33 and 35, suitable angle members 45 and 46 are secured to the upper side of member 28 which limit the clockwise movements of members 33 and 35. In order to accomplish this purpose for members 38 and 39 plates 47 and 48 are provided which limit the clockwise movement of these members.

Pivotedly secured to the back of arm rests 37 and 43 is a link 50, (see Figure 3), and secured to the front side of these members is a strap 51 which has a snap 52 on the end thereof for engaging a ring 53, said ring being secured in the arm rest 43. This acts as a guard for small children to prevent them from falling off of the seat. By observing Figures 1 and 3 it is seen that plate 20 extends some distance beyond the rod 25 and has pivotally mounted in the end thereof as at 54, a link 55, said link 55 extending upwardly and to the right in Figure 3 and being secured as at 56 to upright member 35. By providing link 55 pivoted some distance away from the rod 25 which is the pivot for the entire structure, it is evident that as this toilet seat is folded in a counter-clockwise manner about rod 25 that due to the

eccentricity of the point 54, the uprights 33, 35, 38, and 39 will be caused to rotate in a counter-clockwise manner about their pivot points 32, 34, 40, and 41 respectively, as the seat is rotated upwardly about rod 25 to the position shown in Figure 5. When one quarter of a revolution has been made, the uprights and their associated parts will occupy a plane parallel to that of the seat 28. Link 50 also serves as a back piece.

10 An eyelet 57 is provided in the end of member 27 and is adapted to be engaged by the hook 58 on the end of cord 59, said cord being secured as at 60 to side wall 10. By providing cord 59 with hook 58 thereon, the toilet seat may be folded 15 and held in the position shown in Figure 5 when not in use. When it is desired to use this toilet seat the hook 58 may be released from the eyelet 57 and the parts lowered to the position shown in Figures 2 and 3. By using a fixture of this 20 type it is only necessary to fold back the conventional toilet seat for adults and lower this in position for children.

Figures 6 and 7 show a modified form of mounting for my apparatus. In some cases where 25 a sidewall is not available, it is necessary to mount the fixtures to the back wall. In Figure 6 I have shown a suitable bracket 61 secured by any suitable means such as screws 62 to a backwall 10a. The outstanding leg of this bracket 30 (Figure 7) has a groove 63 therein and also a slot 64 which is adapted to be penetrated by bolts 65, said bolts 65 penetrating suitable holes in supporting member 66. This slot 64 provides means whereby member 66 may be adjusted with relation to the bracket 61. The end nearest the observer in Figure 6 has an L-shaped portion 66a which is penetrated by a rod 67, said rod 67 also penetrates an angle member 68 which is secured to the side of supporting member 66, and said 35 angle member 68 has pivotally secured as at 69 the link 55 which has been previously described. The rod 67 is adapted to pivotally support the members 26 and 27 upon which the conventional seat 28 is mounted, which is not shown in this

view since it has been previously shown and described in the preferred form.

In the drawings and specification there has been set forth a preferred embodiment of the invention, and although specific terms are employed, they are used in a generic and descriptive sense only and not for purposes of limitation, the scope of the invention being set forth in the appended claims.

I claim:

1. A child's toilet seat adapted to be supported by the conventional toilet seat when in use, comprising a seat member, a pair of arms pivotally secured to the seat member, a back portion pivotally secured to each of the arms, a pair of 15 brackets secured to the wall of the room in which the toilet seat is located, means pivotally securing one end of the seat portion to the said brackets, a link having one end pivotally secured to one of said arms and having its other end pivotally secured to one of said brackets at a point between the pivot point of the seat and the arms so that when the child's toilet seat is raised to approximately vertical position, the link will cause 20 the arms to occupy a folded position parallel to 25 the child's seat portion.

2. A child's toilet seat comprising a pair of members, a seat secured on one end of said members, means for pivotally securing the other ends of said members to the wall of the room in which the seat is located, the child's seat being adapted to be supported by a conventional commode, said seat having a pair of arms pivotally secured thereto, a connecting link pivotally secured at its ends to said arms, a second link pivotally secured 30 to one of the arms at one end and having its other end pivotally secured to a fixed point intermediate the pivot point of the members and the commode so that when the child's seat is swung 35 upwardly on its pivot, the second link will cause 40 the arms to assume a position parallel to the said pair of members.

JAMES S. COTHRAN.
